UNITED STATES PATENT OFFICE.

HENRY G. BRACE, OF NEW YORK, N. Y.

DESIGN FOR A MEDAL.

Specification forming part of Design No. 8,000, dated January 12, 1875; application filed December 12, 1874.
[Term of Patent 3½ years]

To all whom it may concern:

Be it known that I, HENRY G. BRACE, of the city, county, and State of New York, have invented a Design for a Medal, of which the following is a specification:

My design, which is intended for the Centenary of American Independence, is represented in the accompanying photographic illustration, to which reference is made. It consists of a medal in the form of a star, with the head of one the presidents of the United States on each side of each point, including the line from Washington to Grant.

On the center of the side having the first nine presidents, which is to represent 1776, is an allegorical picture of America, showing the Declaration of Independence to Britannia, and holding the American flag unfurled and about to be planted on American soil. Britannia with drawn sword threatens her, defies her independence, and demands surrender. On the center of the other side of the medal, which is intended to represent 1876, is America having succeeded in maintaining her independence, has her rights now fully recognized, and welcomes Britannia, who cordially greets her.

The medal is suspended by a chain from a spread eagle holding the chain in its talons; but the eagle may be dispensed with, if desired.

Having thus described my invention, I claim as new, and desire to secure by Letters Patent—

1. The design for a medal, consisting of the star-shaped form, with the head of a president of the United States on each side of each point, and the two center figures of America and Britannia, substantially as described and shown.

2. The design for a star-shaped medal, eagle, and suspending-chain, substantially as shown.
